[57] CLAIM

The ornamental design for a novelty chair, substantially as shown and described.

DESCRIPTION

FIG. 1 is a perspective view of the novelty chair showing my new design;

FIG. 2 is a side view of my invention shown in FIG. 1.

FIG. 3 is a front elevational view of my novelty chair;

FIG. 4 is a top view of my invention; and

FIG. 5 is a rear view thereof.

The side of the chair not shown is a mirror image of the chair shown in FIG. 2.
